UNITED STATES PATENT OFFICE

95,513

DESIGN FOR A DISPLAY CABINET

Frederick B. Keuthan, Indianapolis, Ind.

Application September 21, 1934, Serial No. 53,354

Term of patent 3½ years

To all whom it may concern:

Be it known that I, Frederick B. Keuthan, a citizen of the United States, residing at Indianapolis, Marion County, Indiana, have invented a new, original, and ornamental Design for a Display Cabinet, of which the following is a specification, reference being had to the accompanying drawing, forming part thereof.

The single figure of the drawing is a perspective view of a display cabinet embodying my design. The shading on the group of panels on the front face of the cabinet, on the group of buttons on the top of the cabinet, and on the several sections of the turned corner posts, indicates that the various panels, buttons, and post sections are of various colors; it being understood that the buttons and panels which are shown plain are also vari-colored. The particular shadings used are not intended to indicate particular colors, but

indicate merely that these various parts are of different colors and shades, without regard for the particular colors or shades used, or for their arrangement.

The dominant features of my design are the variously colored panels which are in the front face of the cabinet, the turned corner-posts with sections of various colors, the top which has a central raised portion between end portions which have pockets for articles to be displayed, and the group of variously colored buttons which are fixed on the upper surface of the central raised portion.

I claim:

The ornamental design for a display cabinet, as shown and described.

In witness whereof, I have hereunto set my hand.

FREDERICK B. KEUTHAN.
